UNITED STATES PATENT OFFICE.

FREDERICK W. MILLAY, OF HAVERHILL, MASSACHUSETTS, ASSIGNOR TO FRED W. MILLAY CO., INC., OF HAVERHILL, MASSACHUSETTS, A CORPORATION OF MASSACHUSETTS.

HINGED LAST.

Application filed June 28, 1923. Serial No. 648,369.

To all whom it may concern:

Be it known that I, FREDERICK W. MILLAY, a citizen of the United States of America, and a resident of Haverhill, in the county of Essex and State of Massachusetts, have invented certain new and useful Improvements in Hinged Lasts, of which the following is a specification.

This invention relates to divided lasts and particularly to the means for retaining the last extended under normal conditions, the object of the invention being to produce a last of this character in which the spring mechanism is so mounted that it will bear directly upon the connecting member between the two parts of the last and cannot become displaced.

The invention consists primarily in a member connecting the forepart of a last to the heel part thereof, and having a lateral socket in one wall thereof intermediate its ends, and in which one end of a spring is positioned, the opposite end of said spring being disposed in a socket in the forepart.

The invention further consists in certain novel features of construction and arrangement of parts which will be understood readily by reference to the description of the drawings, and to the claims to be hereinafter given.

For the purpose of illustrating the invention, one preferred form thereof is shown in the drawings, this form having been found to give satisfactory and reliable results, although it is to be understood that the various instrumentalities of which the invention consists can be variously arranged and organized and the invention is not limited to the precise arrangement and organization of these instrumentalities as herein shown and described, except as required by the scope of the appended claims.

Of the drawings:

Figure 1 represents an elevation of a hinged last embodying the principles of the present invention.

Figure 2 represents a longitudinal vertical section of the same, and

Figure 3 represents a transverse section 50 of the same on line 3, 3 on Fig. 2.

Similar characters indicate like parts throughout the several figures of the drawings.

In the drawings, 10 is the heel part and 55 11 the fore part of a divided last. The heel

part 10 is provided with the usual pin socket 12 and also has another socket 13 extending inwardly from its front face.

In this socket 13 is disposed one end of a tubular member 14, this inserted end being 60 rigidly secured to the heel part 10 by means of the transversely disposed pins 15.

The tubular member 14 is inclined forwardly and downwardly as indicated in Fig. 2 of the drawings, and is positioned within 65 a pocket 16 in the rear end of the fore part 11.

The forward end of the tubular member 14 has a pivot pin 17 extending therethrough and through the fore part 11. 70

The upper and lower walls of the pocket 16 are inclined to each other and are curved to fit the upper and lower surfaces of the tubular member 14.

The front wall of the heel part 10 has a 75 projection 18 extending forwardly therefrom, the front face 19 of which is concaved and adapted to fit the convex portion 20 at the rear of the forepart 11.

The convex face 20 and concaved face 19 80 are concentric to the axis of the pivot pin 17.

At the opposite ends of the convex portion 20 are the shoulders 21, 22 separated from each other a distance greater than the 85 depth of the projection 18.

The shoulder 21 is adapted to coact with the upper face 23 of the projection to limit the movement of the fore part 11 about the pivot 17 when the last is being shortened. 90

When the last is extended as shown in the drawings, the shoulder 22 is in contact with the lower face 24 of the projection 18.

It is desired to have the space between the shoulder 21 and the face 23 free from obstructions under all conditions so that when the fore part is moved about the pivot 17, there will be nothing to hinder the free movement of the fore part 11 about the pivot 17 until the shoulder 21 comes into 100 contact with the face 23.

For this reason, a socket 25 is formed in the fore part 11, extending from the pocket 16, this socket being substantially parallel with the concaved face 19. 105

When the socket 25 has been bored in the fore part 11 its outer end is closed by the plug 26.

The tubular connecting member 14 has an opening 27 in the wall thereof, in which is 110

disposed one end of a spring 28, the opposite end of which is positioned in the socket 25.

By locating the spring 25 in this manner, 5 it is out of the way and cannot be displaced, while a heavier spring may be used than is ordinarily employed in lasts of this character.

There is a further advantage in thus locating the spring substantially parallel with 10 the meeting faces 19, 20, for the reason that when the parts 10, 11 are moved relatively to each other, there will be a direct end-wise action on the spring 25, without any 15 tendency to distort the same.

It is believed that the operation and many advantages of the invention will be understood readily without further description.

Having thus described my invention, I 20 claim:

1. A last comprising a heel part and a fore part; a straight rigid member one end of which is immovably anchored in the heel part while the opposite end thereof extends 25 into a pocket in the fore part and has a transverse cylindrical hole therethrough; a pin in the fore part extending through and fitting said hole; and a hidden spring in a 30 socket communicating with the upper wall of said pocket with its lower end coacting with said rigid member and adapted to force the under wall of said pocket against said rigid member.

2. A last comprising a heel part and a fore part; a straight rigid member one end of which is immovably anchored in the heel part while the opposite end thereof extends 35 into a pocket in the fore part and has a transverse cylindrical hole therethrough; a pin in the fore part extending through and fitting said hole; and a hidden spring in a 40 socket communicating with the upper wall of said pocket with its lower end extending partly through said rigid member, said spring being adapted to force the under wall of said 45 pocket against said rigid member.

3. A last comprising a heel part and a fore part; a tubular member rigidly connected to the heel part and extending into 50 a pocket in the fore part and having a lateral opening in the wall thereof, the width

of said pocket being the same as the diameter of said rigid member; and an unexposed spring, one end of which extends through said opening and coacts with said member, while its opposite end is disposed in a socket in the fore part extending toward the comb thereof, said spring being adapted to force the under wall of said pocket against said tubular member. 55

4. A last comprising a heel part having a forward projection with a concaved face; a fore part having a convex portion at its rear end conforming to said concaved face, with shoulders at opposite ends separated a distance greater than the depth of said projection and adapted to coact with the upper and lower faces of said projection; a tubular member connecting said parts, said member being pivoted to one member and extending into a pocket in the other member the width of which is the same as the diameter of said member; and an unexposed spring mounted in said fore part above said member with one end thereof extending through an opening in the wall of said connecting member, said spring being adapted to force the lower shoulder on said fore part against the bottom of said projection. 65

5. A last comprising a heel part and a fore part, said heel part having a forwardly extending projection provided with a concaved front face and said fore part having rearwardly extending shoulders adapted to coact with upper and lower walls of said projection and a convex face intermediate said shoulders conforming to the concaved face of said projection; a rigid member immovably anchored in said heel part and extending through said projection into a pocket in fore part; an unexposed spring in a socket communicating with said pocket with its lower end extending partly through said rigid connecting member, said spring being adapted to force the under wall of said 70 pocket against said rigid member; and a pin in said fore part extending through a cylindrical hole in the forward end of said connecting member. 75

Signed by me at 746 Old South Bldg., 100 Boston, Mass., this 27th day of June, 1923.

FREDERICK W. MILLAY.
